UNITED STATES PATENT OFFICE.

OSCAR LLOYD DENNES, OF ARDMORE, OKLAHOMA.

ARTICLE-HOLDER.

1,309,844.

Specification of Letters Patent. Patented July 15, 1919.

Application filed April 5, 1919. Serial No. 287,853.

To all whom it may concern:

Be it known that I, OSCAR L. DENNES, a citizen of the United States, residing at Ardmore, in the county of Carter and State 5 of Oklahoma, have invented new and useful Improvements in Article-Holders, of which the following is a specification.

The device which is the subject matter of the present application for patent is designed for securing a bouquet, badge or other article to be worn in the button hole in the lapel of a coat or in any other convenient button hole about the coat or other garments.

15 The invention has for its object to provide a simple and efficient clasp for holding the article, and provided with a button whereby the device is held in place on the garment by inserting the button into the 20 button hole.

The object stated is attained by means of a novel combination and arrangement of parts to be hereinafter described and claimed, and in order that the same may be 25 better understood, reference is had to the accompanying drawing forming a part of this specification.

In the drawing,

Figure 1 is a perspective view showing 30 the application of the invention;

Fig. 2 is a front elevation of the device;

Fig. 3 is a rear elevation of the device, and

Fig. 4 is a cross section on the line 4—4 35 of Fig. 2.

Referring specifically to the drawing, 5 denotes the head of a button provided with a shank 6 which extends from one side of a flat plate 7 of substantially circular 10 contour. On one side of the center of this plate, the latter is formed with an extension 8 having an outstanding marginal flange 9, and on the other side of the center of the plate is an extension 10. The flange 9 forms 15 one of the jaws of a clasp, the other jaw 11 being a similar flange on the lateral extension 12 of a plate 13 pivoted to the plate 7 as shown at 14, the pivot being off the center 20 of the plates. The plate 13 also has a lat-

eral extension 15 similar to the part 10 and 50 located opposite the same.

The plate 13 seats on that side of the plate 7 from which the button shank 6 extends, and in order that it may clear the latter it is recessed, as shown at 16. 55

Around the button shank 6 is coiled a spring having its two ends 17 projecting in the direction of the parts 10 and 15, and bearing against lugs or abutments 18 on the latter. The spring has a normal tendency 60 to turn the two plates 7 and 13 relative to each other in a direction to bring the jaws 9 and 11 together, and upon pressing the finger pieces formed by the parts 10 and 15 together, the plates turn relative to each 65 other to spread the jaws for insertion of the bouquet or other article to be held. The button may then be placed in the button hole to place the bouquet in display position on the garment, or the device can first be 70 placed in the button hole and the bouquet then attached.

The device is very simple in construction, it can be easily and cheaply manufactured, and it is practical and provides a handy 75 and convenient means for holding a small bouquet, flower, badge or other device in display position.

I claim:

A clasp comprising a pair of pivotally 80 connected plates having projecting portions on opposite sides of its center, the projecting portions on one side of the center having outstanding flanges which are opposite each other and form jaws, the projecting portions on the other side of the center forming finger pieces for swinging the plates relative to each other to spread the jaws, a button on one side of the plates, said button having its shank attached to one of the 90 plates, and the other plate being recessed to clear the shank, and a spring anchored to the shank and having its ends engageable with the finger pieces to swing the plates in a direction to bring the jaws together. 95

In testimony whereof I affix my signature.

OSCAR LLOYD DENNES.
